UNITED STATES PATENT OFFICE

SAMUEL S. RIEGEL, OF SCRANTON, PENNSYLVANIA

STEAM DRIER

Application filed May 24, 1927. Serial No. 193,818.

This invention relates to steam separators or driers for use in locomotive boilers and more particularly to a throttle box construction adapted to be arranged within the steam dome of the locomotive for more effectually separating from the entering steam any water that may have been entrained thereby.

It is well known to those skilled in the art to which this invention appertains that entrained water in the steam decreases the degree of superheat attainable which, of course, prevents operation of the locomotive at maximum efficiency at the same time that it decreases the life of the steam engine. There is nothing that removes the lubricant from the cylinder surfaces as effectively as water and it becomes highly important therefore to maintain the cylinders free from this steam entrained water, thus not only permitting the cylinders to be more freely and properly lubricated but also greatly minimizing the wear on piston rods, packing rings, piston heads and other parts of the engine. The removal of entrained water from the entering steam makes the supply to the superheater as nearly dry and clean as possible, thus not only accomplishing large economies by providing the locomotive with a higher degree of superheat but also enabling it to handle increased loads with greater ease and facility.

It is among the principal objects of this invention to obviate the above mentioned objectionable features and difficulties by providing a device which is capable of efficiently and effectively removing the entrained water from the entering steam.

A further object of the invention is the provision of a throttle box construction which is simple in construction and effective in operation, the entrained water being removed from the steam by the action of gravity and capillary attraction.

A still further object of the invention is the provision of a novel and effective manifold for receiving and collecting the moisture cast thereon due to the high velocity of the steam entering the nozzles, these latter conforming in principle to the construction of Venturi tubes for passing the entering steam expansively therethrough into the throttle box.

A still further object of the invention is the provision of a single seated throttle valve of the balanced type which is easily operative to permit the passage therethrough of the steam from which the moisture has been removed.

Other objects, incident to the invention will appear more fully hereinafter in connection with the following description of the accompanying drawings which illustrate a preferred embodiment of the invention.

Figure 1 is a vertical central section through a throttle valve and steam drier embodying the principles of the present invention, the valve being shown seated;

Figure 2 is a view similar to Figure 1 but showing only the valve construction, the valve in this instance being shown unseated; and

Figure 3 is a partial plan and partial section taken on the line 3—3 of Figure 1.

Referring more particularly to the drawings, it will be seen that within the steam dome 10 of the locomotive is located a throttle box, the main body of which is designated generally by the reference numeral 11. The upper portion of this box is provided with the substantially vertically extending stand pipe 12, the lower end of which communicates with the outlet 13 leading to the dry pipe 80 (not shown). Arranged concentrically about the stand pipe 12, and forming an integral part of the main body 11 of the throttle box, is the annular wall 14, this annular wall forming with the exterior surface of the stand pipe 12 a substantially annular chamber 15 for receiving the water as the latter is separated from the entering steam. In order to facilitate the drainage of the water from the chamber 15, the bottom wall 16 thereof is inclined, the chamber being further provided at the lowest point thereof with an outlet 17. A drip pipe 18 has its upper end received within the outlet 17, the lower end of this pipe being provided with a ball check valve or equivalent device 19. Any pressure from above the valve causes the latter to operate so as to permit the water which has been separated from the steam to pass through the 100

valve and back into the boiler to be converted into steam.

Suitably and removably supported between and extending across the intervening space between the wall 14 and the stand pipe 12 is a perforated screen, grid or netting 20 and supported upon this screen 20 are a plurality of closely spaced concentric plates 21 constituting a manifold for collecting the water or moisture thrown off by the steam as it enters the throttle box under high velocity. Preferably, alternate plates of the manifold are corrugated for the purpose of facilitating its action, the water which is collected thereby passing, by its own gravity and capillary attraction, through the screen or netting 20 into the bottom of the chamber 15 from whence it passes through the drip pipe 18 and valve 19 back into the boiler or into the water compartment of the locomotive tender as may be desired.

Suitably mounted upon the upper end of the annular wall 14 is the removable cover plate 22, this plate constituting, when in position, the upper wall sections and top of the steam separating chamber. This top member 22 may be secured in position by any suitable means such, for example, as the bolts 40, taking into lugs on the upper portion of the pipe 12. As is most clearly shown in Figure 1, the plate 22 is spaced vertically above the upper end of the stand pipe 12 and is provided with a plurality of circumferentially spaced steam expanding nozzles 23. These nozzles, which are angularly projected into the separating chamber, are designed to operate substantially in accordance with the principle of operation of Venturi tubes, the nozzles being provided for this purpose with restricted central portions and the ends with oppositely expanding portions. Both the size and number of nozzles employed are sufficient to provide proper steam entrance from the steam dome 10 into the throttle box, the entering steam being forced to pass expansively through the nozzles.

The action of the Venturi nozzles is to increase the velocity of the steam and its entrained water at the restrictions thereof. The water, in being discharged from the nozzles, will continue to travel substantially at the increased velocity in view of the fact that it does not expand appreciably. The entrained particles or drops of water are, therefore, thrown against the set of plates 21 with great force with the result that the water or moisture is very effectively trapped within the separator. It should be noted that further carrying of moisture by the steam is additionally guarded against by the general arrangement of the parts, the same causing the steam to double back on itself before entering the stand pipe 12. In order to control the passage of this steam which has been freed of moisture, there is provided a balanced type of

single seated valve designated generally by the reference numeral 24. For this purpose a removable valve seat 25 is arranged between the bottom end of the stand pipe 12 and the outlet 13. The valve chamber is completed by the provision of a cup shaped member 26 comprising the centrally apertured cap 27 and the substantially cylindrical wall 28, which latter is adapted to be inserted into the main body 11 of the throttle box from the side opposite the outlet 13. Elongated slots 29 are provided in the cylindrical wall 28 of the valve member 26. A stem 30 provided with a suitable stuffing box 31 is longitudinally operable through the aperture in the cap 27 and is provided at its inner end with a pilot valve 32 normally seated against the main valve 33. The stem 30 is provided with an extension 34 projecting beyond the pilot valve 32 and secured to this extension are nuts 35 the inner one of which is adapted to engage the outer surface of the valve 33. A balancing piston 36 secured to and operable with the main valve 33 is arranged within the cylindrical portion 28 of the valve member 26, this balancing piston being provided with an aperture 37 connecting the balancing chamber formed by the piston 36 and the cap portion 27 with the stand pipe 12.

It will be seen that as the stem 30 is actuated by the operating mechanism 38, which latter is suitably hinged at 39 to the cover plate 22, the pilot valve will be drawn outwardly and away from the main valve 33, thus permitting steam to pass through the aperture 37 in the piston 36 and beyond the pilot valve 32. Further outward movement of the stem 30 results in the inner nut 35 engaging the rear face of the main valve 33, whereupon the latter is lifted from its seat 25, there being practically no resistance offered to this unseating due to the fact that there is a continuous release of pressure in the balancing chamber through the pilot during the period that the throttle valve is unseated.

Figure 2 clearly shows the relative arrangement of the parts when the valve 33 is in its operatively open position. To effect reseating or closure of the valve against the passage of the dry steam from the stand pipe 12 to the outlet 13, it is only necessary to operate the actuating mechanism 38 to cause the pilot valve 32 to seat against the main valve 33, thus closing the outlet from the balancing chamber of the valve structure. Further movement of the actuating mechanism, and accordingly of the stem 30, effects further movement of the main valve 33, the piston 36 being returned to its normal position due to the fact that it is arranged to move with the main valve 33.

I claim:

1. In a steam separator, an integral casting including a pair of concentric upstand-

ing walls, means for closing the space between said walls at the bottom thereof, a substantially inverted cup-shaped member supported upon the upper edge of the outer of said walls, and a plurality of steam admission nozzles supported by and spaced circumferentially about the peripheral edge of said member, said nozzles having their inner ends projecting into the space between said concentric walls, together with separator plates in said space.

2. In a steam separator, an integral casting including a pair of concentric upstanding walls, means for closing the space between said walls at the bottom thereof, a cover member supported upon the upper edge of said outer wall with the main body thereof spaced vertically above the upper edge of said inner wall, and a plurality of steam nozzles projecting through said main body of the cover member, each of said nozzles being provided with a restricted central portion and an expanding outlet portion, together with separator plates in the space between said walls.

3. In a steam separator, an integral casting including a pair of concentrically arranged upstanding walls, a grid member extending transversely across the space between said walls, and a plurality of concentric plate members supported upon said grid member, means for directing the steam with its entrained water into said plate members, said grid and plate members constituting a manifold for collecting the water.

4. In a steam separator, a main body member including a pair of outer and inner upstanding walls the space between which is closed at the bottom, a cover member supported upon the outer of said walls and vertically spaced with respect to the top of the inner wall, means for projecting the entrained water at high velocity into the space between said walls, and means disposed within said space for collecting the water.

5. In a steam separator, a main body member including a pair of outer and inner cylindrical walls, means for closing the space between said walls at the bottom thereof, the space inside of the inner of said walls serving as a discharge passage for the steam freed from moisture, means for projecting the steam with its entrained water into the space between said walls, a grid member disposed transversely across said space in position to receive the water to be retained in the boiler, and a plurality of concentrically arranged plates disposed in said space and supported upon said grid, said plates being alternately corrugated.

6. In combination with a steam dome, a separator therein including a closed chamber, an upwardly opening stand-pipe in said chamber communicating with an outlet, separator plates arranged in said chamber

around said stand-pipe and a Venturi nozzle in the wall of the chamber positioned and arranged to admit steam from the dome to the chamber and direct the same toward the separator plates at an angle thereto.

7. A steam and water separator including a plurality of spaced plates arranged side by side and a Venturi nozzle for directing the steam and water against the edges of said plates.

8. A steam and water separator including a chamber having an outlet, a plurality of plates in said chamber arranged side by side and a Venturi nozzle in the wall of said chamber positioned to direct the steam and water angularly against the edges of said plates.

9. The combination of a steam dome with a steam and water separator therein including a substantially closed chamber having an upwardly open stand-pipe for discharge of dried steam, a plurality of cylindrical separator plates spaced from each other and arranged on edge concentrically around the stand-pipe and a plurality of Venturi nozzles in the wall of the chamber arranged in a ring overlying and directed toward said plates for admission of steam and water from the dome into said chamber toward the said plates, whereby the water is violently thrown into the spaces between the plates and the steam is caused to follow a circuitous path to the opening of said stand-pipe.

10. The combination of a steam dome with a steam and water separator therein including a substantially closed chamber having an outlet for dried steam, a plurality of spaced separator plates and a Venturi nozzle in the wall of the chamber for admitting steam and its entrained water from the dome into the chamber, said nozzle being directed toward said plates and away from said outlet, whereby the entrained water is violently thrown into the spaces between the plates and the steam is separated and caused to change its course to reach said outlet.

11. The combination of a steam dome with a steam and water separator therein including a substantially closed chamber having an outlet for dried steam, a plurality of spaced separator plates, a Venturi nozzle in the wall of the chamber for admitting steam with its entrained water from the dome into the chamber, said nozzle being directed toward said plates and means below said plates for collecting the separated water and returning the same to the boiler.

12. The combination of a steam dome with a steam and water separator therein including a substantially closed chamber having an outlet for dried steam, a plurality of spaced separator plates, a Venturi nozzle in the wall of the chamber for admitting steam and its entrained water from the dome into the chamber, said nozzle being directed to

ward said plates and means below said plates for collecting the separated water and returning the same to the boiler including an inclined wall at the bottom of said chamber and a return pipe communicating with the chamber at a point just above the low point of said wall.

13. In a steam separator, a main body member including a pair of outer and inner cylindrical walls, means for closing the space between said walls at the bottom thereof, the space inside the inner of said walls serving as a discharge passage for the steam freed from the moisture, means for projecting the steam with its entrained water into the space between said walls, a grid member disposed transversely across said space in position to receive the water to be retained in the boiler, and a plurality of concentrically arranged plates disposed in said space and supported upon said grid.

14. A combined steam and water separator and throttle mechanism including a ring of spaced separator plates, means for projecting the steam with its entrained water into the spaces between said plates, a dry steam discharge conduit extending upwardly through and opening above said plates and a throttle box communicating with the lower end of said conduit.

15. A combined steam and water separator and throttle mechanism including a ring of spaced separator plates, means for projecting the steam with its entrained water into the spaces between said plates, a dry steam discharge conduit extending upwardly through and opening above said plates, a throttle box communicating with the lower end of said conduit, a balanced piston arranged for movement in said box and a throttle valve operable with said piston.

16. A steam and water separator including a plurality of annular concentric plates and a Venturi nozzle for directing the steam and water against the edges of said plates.

In testimony whereof I have hereunto signed my name.

SAMUEL S. RIEGEL.
